(57) CLAIM

I claim the ornamental design for a spa, as shown and described.

DESCRIPTION

FIG. 1 is a top perspective view of a spa showing my new design;

FIG. 2 is a top plan view thereof;

FIG. 3 is a left side view thereof, right side view being a mirror image; and,

FIG. 4 is a front view thereof, the rear view being a mirror image.

The matter delineated in broken lines forms no part of the claimed ornamental design.

1 Claim, 3 Drawing Sheets
